COMBINED WALL UNIT, SOAP HOLDER AND TRAY FOR A BATHTUB OR THE LIKE

Raymond Wallace Young, Louisville, Ky., assignor to American Standard Inc., New York, N.Y.
Continuation-in-part of design application Ser. No. 18,377
July 24, 1969. This application July 15, 1970, Ser.
No. 24,306

Term of patent 14 years

Int. Cl. D23—02

U.S. Cl. D23—69

FIG. 2

FIG. 1

FIG. 3

FIG. 4

FIG. 1 is a front perspective view of a combined wall unit, soap holder and tray for a bathtub or the like embodying my new design;

FIG. 2 is a front elevational view thereof;

FIG. 3 is a front perspective view thereof showing the tray in its open position; and

FIG. 4 is a longitudinal cross-sectional view taken on line IV-IV of FIG. 1.

This is a continuation-in-part of design application Ser. No. D. 18,377 filed July 24, 1969.

I claim:

The ornamental design for a combined wall unit, soap holder and tray for a bathtub or the like, substantially as shown and described.
